UNITED STATES PATENT OFFICE

CHARLES L. PEIRCE, JR., OF PITTSBURGH, PENNSYLVANIA, ASSIGNOR OF ONE-HALF
TO HUBBARD AND COMPANY, A CORPORATION OF PENNSYLVANIA

SECONDARY RACK

Application filed July 25, 1930. Serial No. 470,603.

This invention relates to insulator supports and more particularly to the type known as secondary racks such as are commonly employed for supporting a number of electric wires on poles, walls or the like, and is a continuation in part of my prior Patent 1,779,489 dated Oct. 28, 1930.

An object of this invention is to provide a device of the type set forth having an improved construction and arrangement.

Another object of this invention is to provide a secondary insulator rack that will be of extremely rugged and simple construction. A further object is to provide a secondary insulator rack in which the insulator supporting parts are made of heavier construction than the parts not subjected to strain.

These and other objects, which will be apparent to those skilled in this particular art, are attained by means of the invention disclosed in the following specification and illustrated in the accompanying drawings, in which

Figure 1 is a view in elevation of a blank formed during the process of manufacturing insulator racks in accordance with one embodiment of this invention;

Fig. 2 is an end view of the blank shown in Fig. 1;

Fig. 3 is a view similar to Fig. 1, showing the finished rack;

Fig. 4 is a side elevation of the rack shown in Fig. 3;

Fig. 5 is a partial view in elevation of a modification;

Fig. 6 is a view in elevation of a modified form of secondary rack;

Fig. 7 is a view in section on line VII—VII of Fig. 6;

Fig. 8 is a view in section on line VIII—VIII of Fig. 6; and

Fig. 9 is a side elevation of the rack shown in Fig. 6.

In the drawings, a secondary insulator rack is shown that is made from a unitary piece of stock metal.

The insulator rack is provided with spaced flanges 5 along each side thereof which form a base for the rack. The side flanges 5 are connected by a central web 6 joined to the

inner edge of the side flanges by legs 7. The central web 6 has spaced thickened transverse members 8 extending across the web and joining the upper ends of the legs 7, each cross member being nearly as thick as 55 the projecting legs 7, as shown in Fig. 2. Connected to the cross members 8 are thickened members 9 which extend outwardly from the web 6 and form the arms of the insulator rack. The arms 9 terminate in a 60 rounded boss 10 which has an opening 12 therethrough for receiving the insulator pin 13 of the usual type on which insulators of the spool type are threaded. Openings 15 are provided in the flanged side members 5 for 65 cooperating with the usual supporting bolt.

The insulator rack can be made either by drop forging or by die rolling a piece of stock metal. In either process, an elongated blank having an irregular cross section is formed. 70 The central web 6 of the elongated blank is provided at spaced intervals with the thickened cross members 8 having longitudinally extending members 9 extending downwardly therefrom and terminating in a rounded boss 75 10, which is formed in the web 6 just above the next cross member 8. The blank so formed is then subjected to cutting and bending operations in which the elongated thickened members 9 and bosses 10 are severed from the middle of the web 6 and bent upwardly to the positions shown in Figs. 3 and 4, wherein they extend outwardly from the cross members 8 to form the insulator supporting arms. 80

The openings 15 in the side members 5 can be formed either during the forging or rolling operation, or during subsequent operations. The severing of the elongated arms 85 from the portion of the web and the bending of the arms upwardly provides a web with elongated openings 16 flanked by web portions 17 which are capable of cooperating with the usual through-bolts commonly employed for supporting secondary racks. The supporting parts of the rack which are subjected to the greatest strain are the cross members 8, and the unitary outwardly extending insulator supporting arms 9 which 90 are formed integrally therewith. These 100

parts are, therefore, made much heavier and thicker than the other parts of the rack.

It will be apparent that the blank can be so formed, if desired, that the insulator supporting arms 9 are connected and extend outwardly from the front face of the thickened cross members 8, as shown in Fig. 5, instead of from the bottom thereof. Such an arrangement will provide a slightly greater reach of insulator supporting arm.

In Figures 6, 7, 8 and 9 I have illustrated a modified secondary insulator rack in which the legs leading from the web to the base portion have been eliminated. This modified form of secondary rack is made from a blank which is formed by either die rolling or die forging. The blank has a base portion 20 provided with transverse portions 21 at regular intervals throughout the length 20 of the blank. Extending downwardly on the blank from the transverse portions 21 are arms 22, which terminate in rounded bosses 23 which are formed in the blank slightly above the next transverse portion 21. The transverse portions 21 and the arms 22 are of greater cross section than the remaining part of the base as is shown in Figures 7 and 8. The arms 22 and bosses 23 are stamped or cut from the base and are bent outwardly 30 to form the insulator supporting arms.

The bosses 23 are provided with openings 24 through which an insulator pin 25 of the usual type is extended for holding the insulators in place upon the supporting arms. Openings 26 are formed at regular intervals along the edges of the base 20, through which fastening means are extended for securing the rack to a wall or pole. In this modification the supporting parts of the rack which 40 are subjected to the greatest strain are the transverse portions 21 and the unitary arms 22 and they are for that reason made heavier and thicker than the remaining parts of the rack.

From the above description, it is readily apparent that a secondary rack of extremely rugged and at the same time simple construction is provided and that it is formed by relatively few steps of standard metal working operations.

Although I have described in detail certain specific forms of this invention and a method of manufacturing the same, it will be apparent that various changes, additions, omissions and substitutions can be made therein without departing from the spirit of the invention and the scope of the appended claims.

What I claim as new and desire to secure 60 by Letters Patent is:

1. A blank for a secondary insulator rack comprising a channel body member having transversely extending members of increased thickness on the web thereof and longitudinally extending members on said web of in-

creased thickness terminating in said transversely extending members.

2. A blank for a secondary insulator rack comprising a body member having spaced transversely extending members of increased thickness and longitudinally extending members of increased thickness, one end of each of said longitudinally extending members terminating in one of said transversely extending members.

3. A secondary insulator rack formed from a single piece of stock metal having spaced side members, a web, legs connecting said side members with said web, thickened transverse members formed integral with said web, and thickened arms formed integral with and extending from said transverse members for forming the arms of said insulator rack.

4. A secondary insulator rack comprising a channel body having integrally formed transversely extending members on the web thereof and of greater thickness than the web, and arms severed from said web and terminating in said transversely extending members for forming insulator supporting members, said arms being of greater thickness than said body portion.

5. A secondary insulator rack comprising a body portion having integrally formed transverse members of increased cross section, integrally formed arms of increased cross section extending longitudinally of said body and terminating in said transverse members, said longitudinally extending arms being adapted to be severed from said body portion and bent out of the plane thereof to form insulator supporting arms.

6. A secondary insulator rack comprising a channel base member, a series of T-shaped members having the tops thereof formed integrally with the web of said channel and an apertured boss on the end of the bottom portion of each of said T-shaped members, said T-shaped members being of greater thickness in section than the web of said channel member.

7. A secondary insulator rack comprising a base, a series of T-shaped members having the tops thereof formed integrally with said base and an apertured boss on the end of each of said T-shaped members.

8. A secondary insulator rack comprising a base, a series of T-shaped members having the tops formed integrally with said base and having the bottoms thereof extending outwardly therefrom and an apertured boss on the end of the bottom portion of each of said T-shaped members for receiving an insulator pin, said T-shaped members being of greater thickness than the thickness of said base.

9. A secondary insulator rack comprising a channeled base, and a series of T-shaped members having the tops thereof formed integrally with the web of said channeled base, the

bottom portion of each of said T-shaped members being bent outwardly from said base to form an insulator supporting arm, said T-shaped members being of greater thickness
5 in section than the web of said channeled base.

In testimony whereof, I have hereunto subscribed my name this 24th day of June, 1930.
